UNITED STATES PATENT OFFICE.

ADOLPHE PROSPER D'EGGIS, OF FRIBOURG, SWITZERLAND, ASSIGNOR OF ONE-HALF
TO WALDO ARTHUR MAAS.

DEVICE FOR RAPIDLY BINDING FOLDED SHEETS, PARTS, AND THE LIKE.

Application filed December 6, 1923. Serial No. 678,884.

To all whom it may concern:

Be it known that I, ADOLPHE PROSPER D'Eggis, of Fribourg, Switzerland, a citizen of the Confederation of Switzerland, have 5 invented certain new and useful Improvements in or Relating to Devices for Rapidly Binding Folded Sheets, Parts, and the like, of which the following is a specification.

10 The present invention relates to means for rapidly binding together folded sheets, such as, for instance, periodicals, book parts, music, and the like, and has for its object an improved method of rapidly binding 15 such parts and the like.

According to this invention I provide a binding device comprising a book casing or cover, inside which is secured on one side of the back at least one tape of strong 20 fabric, and on the other side of the back, a strip of rigid material constituting one leaf of a hinge, perforated opposite each tape in order to permit the said tape to be passed through the said strip, and carrying on its 25 edge, in the vicinity of each of said perforations, a movable resilient clamp with a positive action adapted to pinch both the tape and the said strip, thereby securing the former in position.

30 Each of said tapes is adapted to be passed into the free space provided by a wire fastener or stitch of suitable shape secured to the back of the sheets or book parts to be bound, and adapted to receive said tape.

35 The said wire fastener or stitch is of such shape as to have at least one flat arched portion projecting outwardly from the portion of the stitch which is external to the sheets or book parts, so as to provide for the 40 said free space. The folded sheets or parts of book, periodicals, music, or the like, may be already stitched with said fasteners by the publisher, in which case the said parts or the like may be secured at once in the 45 cover. As an alternative, the material to be placed in the binder may have a strip of strong fabric, as shown at *g*, preferably gummed on one side and having fasteners attached to the other side, secured to the 50 edges thereof to be bound. When the desired number of periodicals or whatever is to be bound are provided with the strips *g* they may be placed between the back cover and retained in the manner above described 55 to form a complete book.

Referring to the drawings:

Figure 1 is a detail view of my metallic binding fastener.

Figure 2 is a view showing in dotted lines my fastener applied to sheets to be bound, 60 said sheets being in open position.

Figure 3 is a view of the fastener applied to sheets, said sheets being partially closed.

Figure 4 illustrates a plurality of sheets supplied with my improved fasteners and 65 having a tape passed therethrough.

Fig. 5 shows the cover provided with the tapes and hinged strip;

Figure 6 illustrates a plurality of sheets supplied with my improved fasteners 70 secured to a special binding strip.

The fastener or stitch at the back or a book part or book of folded sheets is shaped as shown in Figs. 1, 2 and 3, the external portion *a* of the stitch forming a free space 75 at the back *b* of the book, as shown in Fig. 3. The two branches of the fastener, bent back against the external portion *a*, maintain without play the sheets of the book in the usual manner (Figs. 4 and 6). *A* is the 80 book casing or cover within which are disposed along the back, on one side, one or more tapes *c* (Fig. 5), corresponding in width to the space formed by the flat arched portions of the fastener, and on the other 85 side, the strip of rigid material *C*, constituting a hinge and provided with perforations *f* opposite to and in alignment with each tape through which each said tape may pass. In the operative position the free portion of 90 the tape is threaded thru said perforations folded back upon the edge of the strip *C* and is maintained by means of the movable clamp *d*, which is lowered upon it so as to pinch the tape upon the strip. 95

When one wishes to bind the parts of a periodical, for instance, provided with fasteners or stitches with flat arched portions as described above, it suffices to pass the tape into the free space formed between the 100 portion *a* of the fastener and the back *b*, slip it through the perforated strip *C*, and finally secure it by means of the clamp *d*. The following parts will then be inserted in exactly the same fashion until the volume 105 is completed. It can then be placed as it is on a book-shelf.

With the arrangement above described, the tape lies with its whole width against the back of the book-parts to be bound, 110

2
thereby securing a perfectly even fitting of all the said book-parts. The piercings are spaced sufficiently, so that the backs of the book-parts are not weakened, and the fasteners will not come apart, thereby tearing the backs of the book-parts, when the weight of same is allowed to bear on the tape. Also, with the clamping arrangement described, the book may be held in any position without fear of the leaves coming loose.

What I claim and desire to secure by Letters Patent is:—

1. In a binding device, a book cover, a longitudinal strip of rigid material hinged inside the said cover along one side of the back thereof, at least one tape of strong fabric secured inside the said cover on the other side of the back thereof, at least one movable resilient positive-action clamping device, one for each tape, mounted on the edge of the said strip and fasteners adapted to be secured to the back of folded sheets, book-parts and the like to be bound, each fastener being formed with a central part *a* having offset parts, adapted to bear against the back of the folded sheets, and pin portions adapted to pierce the back of said folded sheets and be bent toward each other so as to grip the sheet inwardly of the piercings, each said tape being passed through the free space of said fastener so

as to bear for its whole width against the back of said folded sheet and through a corresponding perforation in said strip and being clamped on the edge of said strip by said movable clamp.

2. In a binding device, a book cover, a longitudinal strip of rigid material hinged inside the said cover along one side of the back thereof, at least one tape of strong fabric secured inside the said cover on the other side of the back thereof, at least one movable resilient positive-action clamping device, one for each tape, mounted on the edge of the said strip, in combination with strips of strong fabric folded longitudinally, adapted to be stuck on the back of said folded sheets, and fasteners secured to the back thereof, said fasteners being formed with a central part *a* having offset parts, adapted to bear against the back of the folded sheets, and pin portions adapted to pierce the back of said folded sheets so as to grip same inwardly of the piercings, each said tape being passed through the free space of said fastener so as to bear for its whole width against the back of said folded sheet, and through a corresponding perforation in said strip and being clamped on the edge of said strip by said movable clamp.

In testimony whereof I affix my signature.

ADOLPHE PROSPER d'EGGIS.
